UNITED STATES PATENT OFFICE.

HORACE H. NEWSOM, OF CLEVELAND, OHIO, ASSIGNOR, BY MESNE ASSIGNMENTS, TO THE STANDARD PARTS COMPANY, OF CLEVELAND, OHIO, A CORPORATION OF OHIO.

WORKMAN'S-CARD PROTECTOR.

1,291,608.

Specification of Letters Patent. Patented Jan. 14, 1919.

Application filed May 26, 1916. Serial No. 100,166.

To all whom it may concern:

Be it known that I, HORACE H. NEWSOM, a citizen of the United States, residing at Cleveland, in the county of Cuyahoga and 5 State of Ohio, have invented a certain new and useful Improvement in Workmen's Card Protectors, of which the following is a full, clear, and exact description, reference being had to the accompanying drawings.

10 This invention relates to a device or apparatus for containing and dealing, in a predetermined order, workmen's time cards, the device protecting the cards against disarrangement or handling, and at the same time 15 revealing a portion of each card, so that the workman may make appropriate notations thereon as to the progress of the work. The apparatus may further serve to count the cards or announce the deliverance of each 20 card, thereby indicating that the piece of work represented by such card is completed.

Difficulty has been experienced in large manufacturing concerns, where it is necessary to apportion the work among the employees by supplying each with a batch of cards representing the pieces of work delegated to him, by the workman arranging the cards to suit his own convenience and pleasure, attending to the more easily performed tasks first, and allowing the more difficult pieces of work to accumulate, thus throwing out of order the system or program arranged by the foreman or other party primarily responsible for the work.

35 It is the fundamental object of this invention, therefore, to provide a comparatively simple device or apparatus for containing a batch of time cards, wherein they may be placed in a predetermined order and dealt, 40 by means of conveniently operated mechanism, through the device (in the present embodiment, from a storage receptacle to a receiving receptacle), a portion of each card being revealed through an opening while 45 passing through the device, so that the workman may record thereon certain facts pertaining to the piece of work represented by the respective cards.

A further object contemplated by my invention is the provision of a suitable counter or annunciator, preferably electrically connected with the device or apparatus, whereby the issuance of each card is recorded at a place where it may be observed by the party 55 in charge.

Further objects will become apparent as this description proceeds, among them being the provision of novel mechanism for positively and accurately feeding the cards; the provision of means for holding the cards 60 against material backward movement; and the provision of an adjustment for adapting the machine to cards of varying thicknesses.

I have illustrated in the accompanying drawings an embodiment of my invention, 65 and while I will proceed to describe the same in detail, I wish to be understood as not limiting myself to the structural details thereof further than is required by the terms of the annexed claims, and is rendered necessary by the state of the prior art.

In the drawings, Figure 1 is a perspective view of the device of my invention; Fig. 2 is a longitudinal section of the same; Fig. 3 is an enlarged sectional detail of a part of 75 the feeding mechanism, the same being taken on the line 3—3 of Fig. 4; Fig. 4 is a transverse section on the line 4—4 of Fig. 2, and looking in the direction of the arrows; Fig. 5 is a similar view, on the line 5—5 of Fig. 2, 80 and looking in the direction of Fig. 4, the present figure including a diagrammatic representation of a counter and an electric circuit through which the same is operatively connected to the device; and Fig. 6 85 shows, in perspective, a workman's time card that may be used in connection with my device.

The embodiment of my invention shown herein is intended to be incorporated in a 90 table or suitable cabinet. For the purpose of this description, it will be assumed that the device is built into a table, the top being represented at 1, and provided with an opening 2, of appropriate shape, for the accommodation of the device.

The device comprises a substantially rectangular frame 5, having an offset 6 at one side, for a part of the feeding mechanism, as will be hereinafter described, and a storage receptacle 7, in the form of a rectangular casing, is shown as formed integral with and rising from one end of the frame 5. A suitable cover 8 closes the top of the storage receptacle, the cover having a hinge 100 connection at 9 with one end of the receptacle, and adapted to be secured in closed position, to the opposite end of the receptacle, by a suitable lock shown in a general way at 10. A ledge 12 extends 105

along each side and across the end of the frame 5, beyond the receptacle 7, and supports two glass panels 13 and 14 that have their adjacent edges separated to leave a space therebetween through which access may be had to a portion of a card, as will be more fully explained hereinafter. The glass panels are held in their respective positions and against the flange 12 by a suitable binder 15 that corresponds substantially in shape to that portion of the frame 5 beyond the receptacle 7, the binder comprising a lip to which the numeral 15 is applied and which overhangs the edges of the glass panels 13 and 14, and is connected through a body portion 16, to a horizontal flange 17 that is clamped between a corresponding flange 18 of the frame 5, and the horizontal wall of a rabbeted portion of the table top which surrounds the opening 2. Screws 19 serve to hold the frame 5 and the binder 15 within the opening of the table top. Between the separated edges of the glass panels 13 and 14, the binder 15 is drawn downward to substantially the plane of the underneath surfaces of the glass, as shown at 20, thus retaining the glass panels against displacement in a direction toward each other. The space thus provided will be referred to hereinafter as the opening, or writing opening, 21.

The screws 19, which connect the end of the frame 5 adjacent the storage receptacle 7 to the table top, also serve to support the plate 22, having spaced bosses through which screws 23 are threaded, the screws being provided with knurled heads, and with knurled lock nuts 24. A similar screw 25, having a lock nut 26 is supported within the boss of a plate 28 which extends across the frame 5 beneath the opening 21, the ends of the plate 28 being clamped to the frame by the opposed screws 19. The upper ends of the screws 23 and 25 are swiveled within a card-supporting plate 30 which preferably extends entirely across the bottom of the storage receptacle 7, and forward thereof a distance beyond the writing opening 21, where its end is turned downward to discharge the cards into a receiving receptacle 32. For convenience of description, the right hand end of the device, as viewed in Fig. 2, will be considered the front. To deflect the free ends of the cards downward as they are fed beyond the supporting plate, I provide a web 33, having a forwardly and downwardly inclined surface, and located within the angle between the front end of the frame 5 and the adjacent portion of the glass panel 14.

The cards are represented at C, and a batch of such cards is shown as contained within the storage receptacle, and are held firmly against the supporting plate 30, by a weight 35. The supporting plate may be

adjusted vertically, by means of the screws 23 and 25, to space it from the lower edge of the front wall of the storage receptacle 7 a distance enough greater than the thickness of a card (but no more) to permit the free passage of a card through the space between the plate and said wall of the receptacle. The screws 23 and 25 thus provide means for conveniently adjusting the device to adapt it to cards of varying thicknesses, the lock nuts 24 and 26 serving to maintain the proper adjustment.

Substantially central of the storage receptacle 7 and also between its forward end and the writing opening 21, the card supporting plate 30 is provided with the respective openings 36 and 37, through which feed rollers 38 and 39, respectively, are adapted to be projected for engagement with the underneath surfaces of the cards as they pass across the supporting plate. The rollers are fixed to the respective shafts 40 and 41, and these shafts have their ends guided in notches in the sides of the frame 5 (see Figs. 3 and 4) and lie, as it were, upon springs 42, which are carried by bosses 43, depending from the supporting plate 30, and located, one on each side of the longitudinal center of the plate. Where the shafts 40 and 41 extend into the offset 6 of the frame 5, they are provided each with a gear 45, that is mounted loosely upon the shaft and having an enlarged hub 46 that is provided with pockets 48, the outer walls of which are eccentric with respect to the shaft, and which contain balls 49 (or the equivalents thereof). This constitutes a ball clutch connection of a well known type, between each of the gears 45 and its respective shaft. A rack carrying plate 50 occupies the offset 6 and is slotted to accommodate the shafts 40 and 41, and above each shaft a rack 51 is attached to the plate 50 and co-operates with the adjacent gear 45. An extension 52 of the plate 50 rises through the slot 53, in the frame 5, and is provided with a suitable finger hold 52^a, whereby the plate may be drawn toward the front of the machine, against the tension of a spring 54, which has one of its ends anchored to the rear end of the offset 6 of the frame 5, and its opposite end attached to the adjacent end of the plate. Thus it will be seen that upon the forward movement of the plate 50, the gears 45, and, through the ball clutches above described, the shafts 40 and 41, with their respective rollers 38 and 39, will be rotated in a direction to feed the cards toward the front of the machine. Due to the ratchet connection between the gears and the shafts, the plate 50 may be drawn forward as many times as is necessary, and to any extent required to properly locate the card beneath the writing opening 21 and then, being released, will return to normal position.

tion without affecting the cards. It will also be observed from the nature of the ball ratchets, that the cards cannot be pushed backward, for the gears are held against 5 backward rotation by the racks, and the balls of the clutches act to hold the shafts, and consequently the feed rollers, against backward rotation with respect to the gears. To insure positive action of the rollers 38 10 and 39 upon the cards, the surfaces of the rollers may be roughened by nurling them, as indicated in Figs. 4 and 5, or an equivalent of such may be employed, as the well known expedient of covering the rollers with 15 rubber or the like. A rail 58 that is L-shaped in cross section, has its horizontal flange secured to the underneath surface of the frame 5 by means of screws 59, and serves as a support and guide for the 20 plate 50.

The receiving receptacle 32 has one or 25 more lugs 60 riveted to its rear wall, and these lugs interlock with ears 61 that are connected to the underneath surface of the table top. The forward end of the receptacle is provided with a lock 62, which 30 operates with a keeper 63 that is secured, by screws 64, to the table top, adjacent its front edge.

35 As I have already stated, I propose, in certain embodiments of my invention, to incorporate a counter or an annunciator for recording or indicating the number of cards which pass through the device. My present intention is to electrically actuate such counter or annunciator, and to control the actuating circuit by a pair of contacts, the 40 engaging and disengaging of which are accomplished by the cards.

45 An arrangement for attaining the foregoing end is shown in Fig. 5, wherein it will be observed that a sleeve 65 of insulating material extends vertically through the left hand side of the card-supporting plate 30. A metallic plunger 66 occupies the upper end of the sleeve 65, and is pressed upward by a spring 67 which is interposed between the bottom of the plunger and a screw 68 that is threaded into the lower end of the 50 sleeve 65 and serves, besides, as a binding post for the attachment of an electric conductor 69. Normally, the plunger 66 is forced upward into engagement with a contact member 70 that is carried by the binder

55 15. The binder and frame 5 of the device are "grounded", so to speak, through the wire 71, such wire leading to a battery 72. From the opposite side of the battery a wire 73 leads to the electro-magnet 74 which actuates a counter 75, all of which may be in 60 accordance with common practice, the opposite side of the electro-magnet 74 being connected to the previously mentioned conductor 69.

65 From the foregoing it will be seen that, so

long as a card separates, and occupies the space between, the plunger 66 and contact member 70, the circuit represented by the above enumerated elements will be broken, and the electro-magnet 74 deenergized. As 70 soon, however, as the card is withdrawn from between the plunger and contact member, contact will be made and the electric circuit will be completed to energize the electro-magnet and actuate the counter. It 75 will be understood that the cards follow each other in close succession, with the ends of the cards practically abutting, and in order to provide spaces within the continuous succession of cards through which the contact 80 elements may meet, the upper left hand corner of each card is cut off diagonally, as clearly indicated in Fig. 6. This is found to be the simplest way of providing open 85 spaces through which the contact members 90 may engage, although it is obvious that the sides of the cards might be notched, their lower corners cut off, or the body portions of the cards punched for the accomplishment of the same end.

Having thus described my invention, what I claim is:—

1. In apparatus of the character set forth, the combination of a frame having a transparent covering that is provided with a writing opening, a container rising from one end of the frame and in which the cards may be placed in a given order, a stop against which the forward end of the cards bear, a supporting plate for the cards which 95 is adjustable toward and from said stop, there being sufficient space between the supporting plate and stop to permit egress of a card, said supporting plate having an aperture, a feed roller projecting through 100 said aperture and engaging the underneath surface of the card which bears upon the aforesaid plate, means for yieldingly supporting the roller in contact with the card, mechanism for rotating the roller in a direction 105 to feed the card from the container through the aforesaid frame, and a receiver into which the cards may be discharged as they are fed from the aforesaid container and through the frame. 110

2. In apparatus of the character set forth, the combination of a frame having a writing opening, a container rising from the frame and in which the cards may be placed, a supporting plate for the cards, there being sufficient space between the supporting plate and container to permit egress of a card, said supporting plate having an aperture, a card feeding device projecting through said aperture and engaging the underneath surface of the card which bears upon the aforesaid plate, mechanism for actuating said device to feed the card from the container through the aforesaid frame, and a receiver into which the cards may be 120 125 130

discharged as they are fed from the aforesaid container and through the frame.

3. In apparatus of the character set forth, the combination of a frame, a cover therefor that is provided with a writing opening, a container rising from one end of the frame, a closure for said container, a lock for said closure, a supporting plate extending beneath said container and the cover of the aforesaid frame, an abutment for the forward ends of cards within the container and under which the lowermost card is adapted to be fed into the frame, means for adjusting the aforesaid supporting plate toward and from the aforesaid abutment, there being sufficient space at all times between the supporting plate and abutment to permit the egress of a card, the supporting plate having apertures, and feeding mechanism 15 yieldingly projected through the aforesaid apertures for engagement with the cards upon the supporting plate thereby to feed said cards from the container through the aforesaid frame, a receiver for the cards 20 which is supported beneath the aforesaid frame, and a means for locking said receiver closed.

4. In apparatus of the character set forth, the combination of a frame having a cover 30 that is provided with a writing opening, a container rising from one end of the frame, a supporting plate beneath the container and the cover, there being sufficient space between the supporting plate and container 35 to permit the egress of a card, said plate having openings, rollers located beneath the plate and projecting through said openings, shafts whereon said rollers are secured, means yieldingly supporting the shafts, 40 gears mounted upon the corresponding ends of the shafts, a ratchet connection between each gear and its respective shaft, a rack carrying plate slidably supported within one side of the frame and having an operating handle extending without the frame, 45 and racks carried by the plate for coöperation with the aforesaid gears.

5. In apparatus of the character set forth, the combination of a frame having a cover 50 that is provided with a writing opening, a supporting plate located beneath the cover and spaced substantially the thickness of a card therefrom, said plate having an opening, spring arms secured to the underneath 55 side of the plate, a shaft supported by said

arms, a roller secured to the shaft and projecting through the aforesaid opening of the plate, and means for rotating said shaft.

6. In apparatus of the character set forth, the combination of a frame having a cover 60 that is provided with a writing opening, a supporting plate located beneath the cover and spaced substantially the thickness of a card therefrom, said plate having an opening, spring arms secured to the underneath 65 side of the plate, a shaft supported by said arms, a roller secured to the shaft and projecting through the aforesaid opening of the plate, a driving member rotatable freely upon the shaft, and ratchet connections between said member and the shaft. 70

7. In apparatus of the character set forth, the combination of a frame having a cover that is provided with a writing opening, a supporting plate located beneath the cover 75 and spaced substantially the thickness of a card therefrom, said plate having an opening, a roller projecting through said opening, a shaft to which said roller is secured, means for yieldingly supporting said shaft, 80 a gear mounted upon the shaft, a ratchet connection between said gear and the shaft, a rack slidably supported within the frame for coöperation with the aforesaid gear, and means extending without said frame for reciprocating said rack.

8. In apparatus of the character set forth, the combination of a frame having a cover that is provided with a writing opening, a supporting plate located beneath the cover 90 and spaced substantially the thickness of a card therefrom, said plate having openings that are spaced from each other, a roller projecting through each opening, a shaft to which said roller is secured, a pair of resilient arms for supporting the opposite ends of each shaft, gears supported upon the corresponding ends of the shafts, a ratchet connection between each gear and its respective shaft, a rack carrying plate slidably supported within the frame and having an operating handle extending without said frame, and a rack carried by said plate for coöperation with each of the aforesaid gears. 95 100

In testimony whereof, I hereunto affix my 105 signature in the presence of two witnesses.
